Primary Examiner — Cathron Brooks*Assistant Examiner* — Deanna Fluegeman(57) **CLAIM**

The ornamental design of a display screen with graphical user interface, as shown and described herein.

DESCRIPTION

FIG. 1 is a front view showing my new display screen with graphical user interface.

The broken line showings of the display screen, pictures, patterns, characters, and symbols are for illustrative purposes only and form no part of the claimed design.

1 Claim, 1 Drawing Sheet
